M. V. HULTQVIST.

UNITED STATES PATENT OFFICE.

MORTEN V. HULTQVIST, OF NEW YORK, N. Y.

FLOOR MOP.

Application filed June 23, 1922. Serial No. 570,300.

To all whom it may concern:

Be it known that I, MORTEN V. HULTQVIST, a subject of the King of Sweden, residing at New York, in the county of New York and State of New York, have invented certain new and useful Improvements in Floor Mops, of which the following is a specification.

This invention relates to floor mops and 10 more particularly to those devices wherein the endless strip or woven fabric constituting the mop proper may be twisted by the rotation of the handle so that the water may be "wrung" from the mop.

15 The primary object of my invention is the provision of a floor mop wherein the handle is provided with a supporting sleeve slidable with respect to the lower end of the mop so as to permit the endless strip to be released 20 from its normal position so that it may be twisted and turned as in the act of wringing to rinse the same preliminary to use.

Another and equally important object of my invention is the construction of a floor 25 mop of the character above specified which is extremely simple in construction, easily assembled, consisting of but few parts, highly efficient in operation and use, practical, durable and capable of being manufactured at an extremely low cost whereby its 30 commercial possibilities are greatly enhanced.

I attain the above objects and others which will be apparent as the description proceeds 35 when taken in connection with the drawing and wherein,

Figure 1 is a side view.

Figure 2 is a plan view.

Figure 3 is a reverse perspective showing 40 the mop or endless strip during the act of wringing.

Figure 4 is a detail showing the supporting loop in its relation with the bottom of the handle and,

45 Figure 5 is a detail sectional view of the sleeve and the locking means therefor.

Referring now to the drawings wherein like reference characters designate corresponding parts throughout the several views, 50 5 designates a handle, the lower reduced end 6 thereof being adapted to receive a twisted stout wire wrapped around the same in a series of loops 7^a, the free end of said wire being formed somewhat in the nature of an

ellipse 7, the end 8 of which lies adjacent the reduced portion 6 of the handle and since the resiliency of the wire permits of its bending, the mop 9, consisting of an endless strip, may be passed through the loop 7 as clearly shown by the drawings. It will be observed 55 that the arms 9^a extend slightly forwardly so that the horizontal portion 10^a of the wire is disposed somewhat in the same plane as the handle 5 above referred to. Slidably mounted 60 on the handle 5, I have provided a sliding sleeve designated in its entirety by numeral 10 which sleeve is provided with a pair of horizontally extending lugs 11 which receive the bent inwardly extending ends 12 of a pair of curved supporting arms 13, said arms 65 converging toward the front thereof as at 14 and being bent in the form of a loop 15 substantially the same width as the loop 7 above referred to. The endless strip 9 passing through the respective loops 7 and 15 would 70 naturally lie taut in the position as shown by Figure 1 but when the sleeve 10 is released from the spring pressed button 16 within the handle 5, and slid upwardly thereon since the arms 13 pivot on said 75 sleeve, the mop 9 may thus lie loosely between the supporting loops 7 and 15 whereupon rotation of the handle 5 will wring the mop 80 as is well understood. The tension on the arms 13 due to the rotation of the handle is 85 sufficient to offset the tendency to twist the said arms from their normal position, it being understood that gravity will tend to cause the mop 9 to lie loosely from the end 90 of the handle during the act of wringing and that the twisting and turning will take place from the bottom of the handle gradually toward the loop 15 supporting the opposite end of the mop.

While I have illustrated and described my invention with some degree of particularity, I realize that in practice various alterations therein may be made. I therefore reserve the right and privilege of changing the form of the details of construction or otherwise 95 altering the arrangement of the correlated parts without departing from the spirit of the invention or the scope of the appended 100 claim.

Having thus described my invention, what I claim as new and desire to secure by United States Letters Patent is:—

A combined mop and wringer comprising

a handle, an open loop secured to the lower end of the handle for receiving one end of a mop fabric, a sliding sleeve carried by the handle, a pair of arms having a closed loop at one end thereof, pivotally mounted on the sleeve, means for locking the sleeve adjacent the lower end of the handle whereby

the mop fabric is distended, said sleeve being slidable on the handle permitting the mop fabric to lie loosely between the supporting elements whereby it may be rotated by the handle during the act of wringing.

10

In testimony whereof I affix my signature.
MORTEN V. HULTQVIST. [L. s.]
